UNITED STATES PATENT OFFICE.

REINHOLD F. DE GRAIN, OF WASHINGTON, DISTRICT OF COLUMBIA.

HOISTING AND SUPPORTING DEVICE.

SPECIFICATION forming part of Letters Patent No. 357,185, dated February 8, 1887.

Application filed November 3, 1886. Serial No. 217,868. (No model.)

To all whom it may concern:

Be it known that I, REINHOLD F. DE GRAIN, a citizen of the United States, residing at Washington, in the District of Columbia, have 5 invented a new and useful Hoisting and Supporting Device, of which the following is a specification.

My invention relates to a hoisting and supporting device consisting of pulley and catch-hook to be used for the raising of a permanently-fixed step-ladder and securing the same against the ceiling, reference being had to the accompanying drawings, in which—

Figure 1 is a side view of the complete combination; Fig. 2, a rear view as it appears fastened to the ceiling; Fig. 3, a view of the bottom of the plate; Fig. 4, a vertical section of plate on the line *u v* on Fig. 3; Figs. 5 and 6, the front and side views of hook-support; 20 Fig. 7, a section of hook-support on the line *y z* on Fig. 5; Fig. 8, the front and side views of catch-hook; Fig. 9, the front and side views of spring; Fig. 10, the front and side views of pulley-frame; Fig. 11, the pulley; Fig. 12, 25 the small outside pulley; and Figs. 13 and 14, the bolts through pulley-frame and hook-support, respectively.

Similar letters refer to similar parts throughout the several views.

30 The plate A constitutes the support of the combination, and is so constructed that the heavy part of it will support and brace the weaker part, on which the weight of the step-ladder is suspended, when it is being lowered or raised. Two holes, *c* and *d*, are drilled 35 through plate, the upper half, *b*, of hole *c* to be enlarged, as shown in Fig. 4. To prevent the plate from turning, two small points, *a a*, on the upper side and heavy part of plate 40 have been introduced, which enter the ceiling.

The squares shown in broken lines in the plate A indicate the position in which the pulley-frame and catch-hook support will be after they have been fastened to said plate. The 45 screw *e*—a part of the pulley-frame B—is inserted into the hole *c* in plate A, and a screw-nut, *f*, placed on the screw *e* from the upper side of the plate and tightened. This screw does not extend to the upper edge of 50 plate A. The pulley-frame being securely

fastened, the pulley E is put in and the bolt I run through holes *g g*, from right to left, which will leave space for the small outside pulley, F. This is then put on, and a screw-nut will hold it in its place. A guard of bent 55 wire, *g'*, is placed in such a position as will prevent the cord from slipping off the pulley. The hook-support C holds the catch-hook D, a bolt, H, running through both for that purpose. A spring, G, fastened by a screw, K, 60 is attached to the hook-support on the upper part and rear side of same. This spring presses on the catch-hook and keeps the same in its original position. The hook, not being allowed to move at will, is kept with its highest point, *s*, pressed against an inside shoulder of the hook-support at the place marked *n*. The hook-support has a screw, *p*, which, after a leather washer, *w*, or washer of flexible material is stripped on, passes through the 65 smooth hole *d* in plate A, and through the ceiling into a joist, which is to be selected for the purpose of holding the arrangement.

In using the above-named combination a cord is fastened to the catch-hook, a hole, *i*, 70 being made for that purpose, running over the small outside pulley, F, the cord reaching down to about six feet from the floor, and on which a tassel may be fastened. Then a rope sufficiently strong is passed over the pulley 75 E, and the one end fastened to an iron rod, E', attached to the step-ladder, the other end hanging down loose. This rod must be placed in such a position that while being raised it will strike the catch-hook at or near 80 the place marked *t*. By further pulling the rope the catch-hook moves to the right and allows the rod to pass the point *g*. No more strain being on the hook, the spring G will bring it back to its original position. By letting the rope go the rod, which forms part of the step-ladder, will be caught by the hook and rest securely at *m*. When so at rest, the step-ladder will be one-half inch below the ceiling. In lowering, pull the rope until the 85 step-ladder reaches the ceiling, thus getting the rod above the point *g* of the catch-hook. Take hold of the cord with the other hand, pull it, and the hook moves to the right. Then let the step-ladder go down until the 90 95 100

iron rod has passed the hook. Let go the cord, and both hands are at liberty to manage the rope on which the step-ladder hangs.

What I claim, and desire to secure by Letters

5 Patent, is—

The described hoisting and supporting device, comprising the plate A, the hook D, its

support C, spring G, pulley, and pulley-frame, all substantially as set forth.

REINHOLD F. DE GRAIN.
